United States Patent Office

Des. 208,823
Patented Oct. 3, 1967

208,823

JUG

Harry E. Lowe III, Martinsville, N.J., and Albert B. Mojonnier, Chicago, Ill., assignors to Albert Mojonnier, Inc., Franklin Park, Ill., a corporation of Illinois

Filed Sept. 8, 1966, Ser. No. 3,771

Term of patent 14 years

(Cl. D58—5)

Fig. 1.

Fig. 3.

Fig. 2.

FIGURE 1 is a front and side perspective view of a jug embodying our new design;

FIGURE 2 is a rear and side perspective view thereof; and

FIGURE 3 is a top plan view thereof.

The dominant features of our design reside in the portion shown in full lines.

We claim:

The ornamental design for a jug, substantially as shown and described.
